Primary Examiner — Patricia A Palasik

(57) **CLAIM**

The ornamental design for a ceiling light, as shown and described.

DESCRIPTION

FIG. 1 is a first perspective view of a ceiling light, showing my new design;

FIG. 2 is a front elevational view thereof;

FIG. 3 is a rear elevational view thereof;

FIG. 4 is a left side view thereof;

FIG. 5 is a right side view thereof;

FIG. 6 is a top plan view thereof; and,

FIG. 7 is a bottom plan view thereof; and,

FIG. 8 is an enlarged view of the selected portion 8 in FIG. 1.

The broken lines shown in the drawings depict portions of the ceiling light that form no part of the claimed design.

1 Claim, 8 Drawing Sheets
